(57) **CLAIM**

The ornamental design for a computer display panel with a graphical user interface for a dermatology report, as shown and described.

DESCRIPTION

The FIGURE is a front view of a computer display panel with a graphical user interface for a dermatology report, showing our new design.

The broken lines represent portions of the computer display panel and the graphical user interface that form no part of the claimed designs. Within the broken lines, the broken line showing of text and other features of the dermatology report is for environmental purposes only and forms no part of the claimed designs.

1 Claim, 1 Drawing Sheet

DermTech Melanoma Test
MOLECULAR PATHOLOGY REPORT

PATIENT INFORMATION	
Patient Name	KH/ID/Access ID
Reference #	Body Site
MRI#	Date Collected
DOB (Age)	Date Received
Sex	Date Reported
Referring Physician	Fax Number
Address	City/State/Zip

TEST RESULTS		
MELANOMA-ASSOCIATED GENOMIC ATYPIA:		
Pigmented Lesion Assay (RNA Gene Expression)	TERT Add-On Assay (DNA Mutations)	
☒ LINC00518	☐ PRAME	☐ TERT

Macro-Dissection Report/Comments: The pre-specimen consists of adhesive stickers containing four tissue samples. Except as noted, each sticker contained tissue material which was free of obvious contamination with blood, exudate, hair or other contaminants. Each sticker had a central circle delineating the margin around the tissue material. Examination of each of the macrodissected specimen revealed that the lesional tissue material was excised of the margin. Each sample was submitted for qPCR analysis. Images of all of the macrodissections are kept on file and are available for review. Testing of lesions from patients with Fitzpatrick skin types IV and higher have not been validated but can be ordered with the ordering physician determines the test is medically necessary for patient evaluation. (Macro comment and free text)

INTERPRETATION OF TEST RESULTS & RECOMMENDED CLINICAL MANAGEMENT	
Genomic atypia, based on the detection of LINC00518 and/or PRAME gene expression and TERT DNA promoter mutations, is associated with melanoma.	
The DermTech Melanoma Test is considered positive for genomic atypia if one or more of these biomarkers (LINC00518, PRAME, or TERT) have been detected.	
NEGATIVE	Consider clinical surveillance for changes in appearance.
POSITIVE	Recommend surgical biopsy and histopathologic evaluation.
